UNITED STATES PATENT OFFICE.

JOSEPH F. KELLER, OF NEW YORK, N. Y., ASSIGNOR TO KELLER MECHANICAL ENGRAVING CO., OF BROOKLYN, NEW YORK, A CORPORATION OF NEW YORK.

DIE SINKING, ENGRAVING, REPRODUCING MACHINE AND THE LIKE.

1,351,211.

Specification of Letters Patent. Patented Aug. 31, 1920.

Application filed May 2, 1917. Serial No. 165,871.

To all whom it may concern:

Be it known that I, JOSEPH F. KELLER, a citizen of the United States, residing in the city, county, and State of New York, have 5 invented certain new and useful Improvements in Die Sinking, Engraving, Reproducing Machines and the like, of which the following is a specification.

My invention relates to machines for 10 engraving or sinking dies, or for reproducing in relief or intaglio, and more especially to such machines as are to be employed for reproducing from a templet, model or pattern on either a reduced or an enlarged scale.

15 My invention has for its object to provide a novel machine of the class specified which shall be comparatively simple in construction, have a comparatively small number of parts and which shall at the same time be 20 accurate and reliable.

More particularly still it is the object of my invention to provide a machine of the character described in which the relative three dimensional motions which must take 25 place, as between the tracer and cutter on the one hand and the pattern and the work on the other hand, is entirely due to or associated with a single carrier or operating bar of novel construction, both pattern and work 30 remaining fixed, as originally set up, throughout the operation of the machine.

A further object of my invention is to provide a machine of the character specified, and having my novel type of carrier or 35 operating bar, especially suitable for engraving dies for use in the manufacture of anti-skid and figured treads for automobile and bicycle tires and the like.

My novel form of carrier or operating bar 40 may be embodied in a large variety of die sinking or reproducing machines for various usual or special purposes.

My invention will be better understood by referring to the accompanying drawings, in 45 which Figure 1 represents a front elevation of a preferred form of my invention, as embodied in a machine for engraving dies used in the manufacture of anti-skid treads for automobile or other tires; Fig. 2 is a plan view of Fig. 1; Fig. 3 is an end elevation, taken from the left, of Fig. 1; Fig. 4 is a vertical section, taken along the line 4—4, of Fig. 1; Fig. 5 is a view, taken from the

right, of the end of Fig. 1; Fig. 6 is a front elevation showing the improved carrier bar 55 of my invention as embodied in a simple form of die sinking machine; and Figs. 7 and 8 are, respectively, front and side elevations of a simple form of vertical die sinking or engraving machine embodying my improved carrier bar. 60

In the drawings, Figs. 1 to 5 inclusive, a base 1 carries, at one end, a rear pedestal 2 and a front pedestal 3, the former being bored, in a plane transverse to the base and 65 at an angle of about 45° with the vertical, to receive a shouldered stem or bearing 4, integrally a part of a revoluble turret-like mold carrier 5 provided with an annular flange 6 through which clamp screws 7 are 70 threaded.

The mold carrier is provided with an annular rack 8, and adjacent faces of the mold carrier and bearing 4, with respect to pedestal 3, are carefully fitted and finished for 75 smooth and easy movement upon one another.

The upper surface of flange 6 is graduated and an index 9, mounted upon brackets 10 forming part of the pedestal or housing 2, is 80 disposed adjacent thereto.

A worm 11, in mesh with rack 8, is also mounted in brackets 10 and forms part of a spindle 12 whose outer end is carried by another bracket 13, also attached to housing 85 2. A hand wheel 14 enables worm 11 to be rotated, thus correspondingly rotating the mold carrier upon its bearing.

Pedestal 3 is hollow and surmounted by a transversely slidable cap 15, having keyed 90 relation with the pedestal and provided with a hub 16 projecting down into the pedestal. This hub is bored and the upper face of the cap is machined to coöperate with correspondingly finished surfaces of a carrier 95 arm bearing 17 whose top is formed as a transverse bar 18. This bar 18 has conical centers formed in its ends to receive pointed pivots 19 carried by forks 20 formed near one end and upon the lower side of a carrier or operating bar 21.

The carrier bar, as here shown, is of T shaped section for the sake of stiffness and provided with reinforcing ribs 22, above the pivots.

105 Suitable portions of the horizontal web

of the T bar are faced, and preferably given a dove-tailed section, and upon these portions are mounted the longitudinal slidable cutter carrier 23 and the tracer carrier 24.

5 The cutter carrier is provided with a rearwardly projected bracket 25 which is vertically bored for a spindle carrying a cutter 26 and a grooved pulley 27. Similarly the tracer carrier carries a suitably bored bracket 10 in which is held the fixed but vertically adjustable tracer point 28.

Cutter carrier 23 is also provided with a bracket upon which is pivotally mounted a lever 29, the lower and shorter arm of which 15 is pivotally connected with a link 30 whose other end is pivotally attached at 31 to a lug formed on the carrier bar 21. The other end of lever 29 is slotted and pivotally joined to a link 32 whose outer end is similarly pivoted at 33 to a lug formed on the tracer carrier 24.

Link 32 is three times the length of link 30 and the longer arm of lever 29 is three times the length of the shorter arm, the distance 25 in each case being taken between the pivotal points which have been referred to. The cutter and tracer are also so positioned that, in any given position of links 30 and 32 and of lever 29, the distance between cutter 30 and tracer is three times that between the cutter and the line of the pivots 19. Under these circumstances, geometrical considerations show that for every position of the cutter and tracer carriers the distance 35 between cutter and tracer will always be three times that between cutter and pivots 19, or, in other words, that the distance between pivots 19 and the tracer will always be four times that between pivots and cutter.

40 At the tracer end of the machine is a third pedestal 34 in the top of which are formed transverse undercut slideways to receive a similarly formed slidable pattern carrier 35, a screw 36, adapted to receive a 45 suitable handle, being used to effect its sliding motion.

At the outer margin of pedestal 34 is another transverse slideway 37 upon which is mounted a slide 38 carrying a pin 39. This 50 slide is provided with a rack on its under surface which is in mesh with a pinion 40 adapted to be rotated by means of a hand wheel 41.

Pin 39 lies loosely between a pair of transversely spaced rollers 42 carried upon arms 43 fixed to the lower side of the carrier bar 21.

Mounted upon the left hand end of the carrier bar is a motor 44 provided with a 60 pulley 45. Idler pulleys 46, 47 and 48 are carried upon other brackets appropriately located upon the carrier bar.

The slidable cutter carrier 23 carries an attached idler pulley 49.

65 A belt 50 passes from the motor pulley

45 around pulleys 46, 47, the cutter pulley 27, idler pulley 49 and idler pulley 48 back to pulley 45.

It will be noted that idler pulleys 47 and 48, are, respectively, adjacent to opposite edges of the carrier bar, thus enabling the belt 50 to be given an S shaped loop over the idler pulley 49 and the cutter pulley 27, both carried by the cutter carrier 22. As the cutter carrier is moved to or from longitudinally on the carrier bar, therefore, the S loop moves with it without either tightening or slackening the belt.

Tracer carrier 24 is provided with an underneath rack 51 in mesh with a pinion 52 mounted on the carrier bar and provided with a hand wheel 53.

The die 54 may be accurately centered and held in the mold carrier 5 by means of the clamp screws 7. It is, of course, understood that this die represents only half of the entire mold or die necessary for the manufacture of a tire, the other half die being exactly the same. In this die only the annular strip lying between the diametral planes passing through points 55 and 56 corresponds to the tread proper and is to be engraved.

Pattern 57 is held in pattern carrier 35 by means of set screws 58 or in any other preferred manner.

In setting up the machine and getting ready for the engraving of a die, the die block 54 should, of course, first have the semi-circularly sectioned annulus, whose 100 surface is to be engraved, turned out upon a lathe or formed in any other preferred way. Furthermore, the pattern 57 should be so adjusted, transversely of the machine, that when the tracer point is immediately above the center of the pattern, the cutter point will be immediately above the periphery of channel or annulus to be engraved which lies midway between the planes of points 55 and 56.

110 Preferably, the height of the pattern should be so adjusted that the lowest point of the die, the lowest point of the pattern, the cutter point, the tracer point and the point in which the axis of pivots 19 intersects the vertical axis of carrier arm bearing 17, all lie in one and the same straight line parallel with the line of travel of the cutter carrier 23 and tracer carrier 24 longitudinally upon the carrier arm. However, 120 should either the die or the pattern, or both, be above or below this line, the cutter or tracer, or both, may be correspondingly adjusted vertically in their respective carriers without substantially varying the accuracy 125 with which the cutter will reproduce the pattern.

The outboard or excess weight of the carrier arm is counterbalanced by a weight 59 at the end of the cord 60 attached to the 130

carrier arm and running over a pulley 61 which may be attached to the ceiling.

A foot pressure lever or treadle 61' is pivoted upon the base 1 and has a cord 62' connected between it and the weight 59. This enables the carrier bar 21 to be readily varied by the operator when it is necessary to change or adjust the cutter or tracer or to inspect the work, change the pattern and 10 the like.

The machine having been set up, as above described, the operation of the same is as follows: The hand wheel 14 is rotated so as to bring the index 9 opposite one of the 15 main or longer divisions of the graduations of the mold carrier. The motor circuit is closed, thus revolving the cutter 26. By now suitably rotating the hand wheel 41, slide 38 may be moved transversely so as to 20 sweep the cutter and tracer points transversely across the die and pattern respectively by means of the pin 39 which presses against one or the other of the rollers 42, hung from the bottom of the carrier bar, 25 and thereby rotates the carrier bar about the axis of its bearing 17. The tracer 28 will follow the contour of the pattern, thus raising the carrier bar or permitting it to lower about the axis of pivots 19 as the 30 irregularities or variations of the pattern may require. The cutter will, therefore, engrave the surface of the die along a line corresponding to the particular line of the pattern which is being traced but the length of 35 this line as well as the depth of the cutting will be reduced, as to the corresponding dimensions of the pattern, in the ratio of 1 to 4. The hand wheel 53 may then be rotated through a small angle, thereby shifting both 40 cutter and tracer longitudinally upon the carrier arm, the extent of movement of the cutter being but one-fourth that of the tracer, however; and the next adjacent line of pattern and die surface be swept over 45 the hand wheel 41 now being turned in the opposite direction; and this operation may be repeated until the entire surface of the pattern has been covered and the corresponding surface of the die has been engraved. 50

If preferred, the successive lines of die and pattern swept over may be longitudinal instead of transverse. In such case the continuous movement of the cutter and tracer points is obtained by a continued rotation 55 of the hand wheel 53 while the intermittent movement necessary to bring the cutter and tracer over adjacent lines is obtained by intermittent rotation of hand wheel 41.

60 Instead of cutting or engraving the die by a systematic sweeping of its surface, as above described, the operator may, if he prefers, proceed irregularly by rotating either or both hand wheels 41 and 53 at will.

65 In this way parts of the figure to be en-

graved, which relatively involve more and finer detail, may be given correspondingly more attention.

Anti-skid and other figured automobile tires are, as is well known, usually provided with a peripheral design which consists of a repetition of some elemental design; thus, for example, where the main design is a chain encircling the tread, the elemental design will be a group of links, the component 70 parts of which are definitely related to one another. In engraving the die, therefore, it is merely necessary that the pattern should embody this elemental design. When a given region of the die lying between a pair 75 of radial planes 62, 63 (Fig. 1) has, therefore, been completely engraved in correspondence with the pattern, the entire die is rotated by means of the hand wheel 14 through an angle corresponding to the angle 80 intercepted between these planes, first, preferably, raising the carrier bar 21 by means of the treadle 61'. A second region of the die is then engraved as before. This operation is repeated until the entire die surface 85 90 has been gone over and engraved. These successive angular rotations of the die may be accurately performed by the aid of the graduated flange 6 and the index 9.

As above described, the reproduction will 95 have dimensions which are accurately one-fourth those of the pattern. Inasmuch, however, as the size or dimensions of the finished work is generally of the utmost importance and as the pattern, which is often 100 made of plaster or of some easily workable composition, may easily turn out to be a little smaller or a little larger than it was intended to be, it is desirable to so arrange that any such error may be compensated for. 105 This I do by means of the slots 64, 64', formed respectively in the outer end of the longer arm of lever 29 and in one end of link 30. By slightly shifting the point of connection of link 32 in the one slot and of 110 lever 29 in the other slot so as to shorten or lengthen the longer arm of lever 29 and the link 30 by the same proportionate amount, the tracer point will be correspondingly moved a little farther away from, or a little 115 nearer to, the cutter point, and the ratio of reproduction, similarly, slightly changed. For this purpose suitable graduations may be placed upon lever 29 and link 30 adjacent to the slots. 120

Fig. 6 shows my improved carrier bar embodied in a very simple form of plain die sinking or engraving machine. Here the carrier bar 21 is shown as circular in cross-section and provided near one end with a 125 bifurcated bracket 65 whose extremities are pivoted to a transverse bearing 66 which is itself pivoted between vertically disposed center points held by a bearing bracket 67. This bracket is pivotally supported upon an 130

axis 67^a passing through the intersection of the axes about which carrier bar 21 is movable, the operating point of center 26 and the contact point of tracer 28. A clamp 5 screw 67^b passing through a slot in bracket 67 and threaded into the extension 67^c, fixed to base 1, enables the bracket 67 to be fixed in any chosen position.

Carrier arm 21', instead of being counterbalanced by a cord and weight, as in the machine of Figs. 1 to 5, is provided with a weight 68 suitably fixed and located upon the arm itself.

The arrangement of tracer, cutter, tracer carrier, cutter carrier, magnifying lever and links, driving pulleys and other operative parts, is substantially the same as in the earlier described machine. The arrangement for moving the tracer and cutter carrier longitudinally and for swinging the carrier bar transversely is, however, much more simple in the machine now being discussed than in the previous machine since it comprises merely a handle 69 attached to the tracer carrier. By means of this handle the operator swings the carrier bar in and out transversely and slides the tracer carrier, and hence the cutter carrier, back and forth longitudinally.

30 It is clear that the type of machine shown in Fig. 6 may take a variety of other forms and that it is immaterial whether the sweeping motion which the carrier bar makes parallel with the faces of pattern and die 35 be in a horizontal plane as shown in Fig. 6, in a vertical plane about an upper or lower pivot, or in a vertical plane about a pivot at one side or the other.

In Figs. 7 and 8 are shown, respectively, 40 front and side elevations of still another simple form of die sinking or engraving machine embodying my improved carrier bar. Here the bar hangs centrally from a bracket 70, one end of which is pivoted to 45 swing about a horizontal transverse axis 71, while the other end carries the motor 44. The axis 71 includes a block 72 which is itself pivoted between horizontally disposed centers 73 at right angles to said axis and 50 carried by the main frame of the machine.

A balancing weight 74 is fixed upon an out board extension of bracket 70.

Tracer point 28 and cutter 26 are held, by tracer carrier and cutter carrier respectively, parallel to the carrier arm and in a line passing through the intersection of axis 71 with the line of centers 73.

60 The operator controls the movement of the cutter by the handle 69, through which he causes the tracer point to move over the surface of the pattern, thereby correspondingly moving the cutter point over the surface of the die.

As the maximum angular movement of the 65 carrier arm, with reference to the vertical,

is comparatively small, no provision has been made in this form of the machine for compensating for any tightening or slackening of the driving belt, as it is believed that this will be but trifling and of no practical importance. Compensating means may easily be arranged, however, by those skilled in the art.

The several machines above described have all been arranged for a ratio of reproduction of 1 to 4. It is clear, however, that the principle of my invention does not require that any particular ratio of reproduction is employed; on the contrary the invention may be readily adapted to any desired ratio of reproduction. Similarly, while the described machines are all arranged to reproduce the dies on a smaller scale than the pattern, it is merely necessary to exchange the pattern and the die and to make some trifling corresponding changes in the operative parts, such changes being easily within the ability of those skilled in the art, to cause the reproduction to be on a larger scale than the pattern.

90 It will also be clear that my invention may be made fully or partially automatic instead of being hand operated as herein described. For this purpose any one of numerous arrangements which have been applied to engraving and reproducing machines of the prior art may be employed.

Having described my invention, I claim:

1. In a machine of the character described, a carrier bar mounted to swing about a universal joint, a tracer point and a cutter, both slidably mounted upon said bar, and means connecting tracer point and cutter whereby they can be slid simultaneously, the ratio of the distances of the tracer point and the cutter respectively from the center of the joint remaining constant for all positions of said tracer point and cutter.

2. In a machine of the character described, a carrier bar mounted to swing about a universal joint, a tracer point member and a cutter member both slidably mounted upon said bar, a lever pivotally attached to one of said members, and a pair of links pivotally attached respectively between an end of the lever and the bar and between the other end of the lever and the remaining member.

3. In a machine of the character described, a carrier bar mounted to swing about a universal joint, a tracer point member and a cutter member both slidably mounted upon said bar, a lever pivotally attached to one of said members, and a pair of links pivotally attached respectively between an end of the lever and the bar and between the other end of the bar and the remaining member, the ratio of the lengths of the links to one another being the same as that of their adjacent lever arms.

4. In a machine of the character described,

- a carrier bar mounted to swing about a universal joint, a tracer point and a rotatable pulley provided cutter, both slidably mounted upon said bar, the cutter being between 5
said joint and tracer point, means for simultaneously sliding cutter and tracer point through distances respectively proportional to their distances from the center of the joint, a motor provided with a pulley 10 and fixed upon said bar, and idler pulleys respectively fixed to the bar between tracer point and cutter and to the cutter mounting between cutter axis and motor.
5. In a machine of the character described, 15 a carrier bar mounted to swing about a universal joint, a tracer point member and a cutter member both slidably mounted upon said bar, a lever pivotally attached to one of said members, a pair of links pivotally attached respectively between an end of the lever and the bar and between the other end of the bar and the remaining member, the ratio of the lengths of the links to one another being the same as that of their adjacent lever arms, and coöoperating rack and pinion members attached one to the tracer point mounting and one to the carrier bar.
6. In a machine for sinking tire molds, a pattern carrier, a rotatable mold carrier having its face inclined to the plane of the pattern carrier face, a carrier bar, a universal joint for said bar adjacent to the mold carrier on the side remote from the pattern carrier, a tracer point and a cutter both slidably held upon said bar normal thereto and parallel to one another, the former above the pattern carrier and the latter above the mold carrier, and means for simultaneously sliding tracer point and cutter through distances respectively proportional to their distances from the center of the joint.
7. In a machine for sinking tire molds, a pattern carrier, a rotatable mold carrier having its face inclined to the plane of the pattern carrier face, means for intermittently rotating the mold carrier through successive 30 35 40 45
- equal angles, a carrier bar, a universal joint for said bar adjacent to the mold carrier on the side remote from the pattern carrier, a tracer point and a cutter both slidably held upon said bar normal thereto and parallel to one another, the former above the pattern carrier and the latter above the mold carrier, and means for simultaneously sliding tracer point and cutter through distances respectively proportional to their distances from the center of the joint.
8. In a machine for sinking tire molds, a pattern carrier, a rotatable mold carrier having its face inclined to the plane of the pattern carrier face and provided with graduations, means for intermittently rotating the mold carrier through measured angles as determined by the graduations, a carrier bar, a universal joint for said bar adjacent to the mold carrier on the side remote from the pattern carrier, a tracer point and a cutter both slidably held upon said bar normal thereto and parallel to one another, the former above the pattern carrier and the latter above the mold carrier, and means for simultaneously sliding tracer point and cutter through distances respectively proportional to their distances from the center of the joint.
9. In a machine of the character described, a carrier bar mounted to swing about a universal joint, a tracer point and a rotatable pulley-provided cutter both slidably mounted upon said bar, means for simultaneously sliding cutter and tracer point through distances respectively proportional to their distances from the center of the joint, a motor provided with a pulley and fixed upon said bar, and idler pulleys respectively fixed to the bar and to the cutter mounting, the latter pulley being between the cutter and the motor.

In testimony whereof I have hereunto set my hand.

JOSEPH F. KELLER.
